UNITED STATES PATENT OFFICE.

LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

COMPRESSOR-REGULATING APPARATUS.

Application filed August 3, 1925. Serial No. 47,829.

This invention relates to apparatus for automatically controlling the operation of compressors, pumps, and the like. It is particularly adapted and intended for use with compressors operated by prime movers having a low starting torque such as the squirrel cage type of electric motor.

With automatic start and stop control apparatus for prime movers of the type described it is essential that the motor be allowed to attain full speed before the compressor loads up. Otherwise serious disturbances and possible damage to the prime mover are liable to occur.

Among the objects of the invention are to provide simple and positively operating apparatus which will delay the loading of the compressor until the prime mover has attained full speed, which is applicable to centrifugal control apparatus already in use, which is adjustable, which is inexpensive to manufacture and install, and in general to improve prior devices in the interests of more efficient and satisfactory service.

In order to illustrate the invention one concrete embodiment thereof is shown in the accompanying drawing in which:

Fig. 1 is a side elevational view of a compressor equipped with automatic controlling apparatus;

Fig. 2 is a vertical sectional view of the controlling apparatus shown in Fig. 1 and indicating the connection to the valves controlled thereby, the latter being also shown in vertical section; and

Fig. 3 is a vertical sectional view similar to Fig. 2, of the controlling device alone, with the parts thereof shown in a different position.

The invention is illustrated as applied to a compressor A of the reciprocating piston type having fluid pressure operated unloading valves *a* which normally operate as inlet valves, and having a water connection B to cool the compressor cylinder under control of a fluid pressure operated valve *b*. The compressor is arranged to be driven by a prime mover having a low starting torque, such as a squirrel cage electric motor (not shown, through a suitable driving connection such as a belt C engaging a fly-wheel D mounted on the crank shaft E of the compressor. The supply and exhaust of the compressed fluid to and from the unloading valves *a* and water control valve *b* is con-

trolled by a speed responsive device indicated at 4, shown in elevation in Fig. 1 and in section in Figs. 2 and 3. This device is arranged to be driven at a speed proportionate to the speed of the compressor by a suitable connection such as a belt 5 engaging a pulley on shaft E of the compressor and a pulley 6 on device 4.

Referring now to Figs. 2 and 3 the control device 4 has a casing 7 provided with chambers 8 and 9 separated by a partition 10, a bore 10^a serving to connect said chambers. A member 11 having a central bore is disposed in chamber 9 and extends into bore 10^a, said member having a series of radial ports 11^a connecting the bore of member 11 with chamber 9. Radial ports 11^b adjacent to the top of member 11 are arranged to connect the bore of the latter with atmosphere. As indicated member 11 has threaded engagement with a cap plate 12 for casing 7, which plate supports the standard 13 in which is mounted for reciprocatory movement a member 14 carrying a rod or stem 14^a projecting within the bore of member 11 and provided at its lower end with a piston head 14^b controlling ports 11^a. Member 14 also carries a rod 14^c acted upon by a suitable centrifugal organization X of conventional form driven by pulley 6. When the compressor is not running at all or running slowly the parts are in the position shown in Fig. 2 with the valve piston 14^b so disposed as to establish connection between chambers 8 and 9. Chamber 8 is connected to receiver pressure by pipe 8^a and chamber 9 communicates with valves *a* and *b* by pipe 9^a. Thus receiver pressure passes to valves *a* and *b* and holds them inoperative as shown in Fig. 2. When the compressor speeds up the centrifugal organization X forces the reciprocatory element 14^c downwardly so that the valve piston 14^b is disposed below ports 11^a (Fig. 3) thereby closing connection between chambers 8 and 9 and connecting chamber 9 to atmosphere through ports 11^a the bore of port 11 and port 11^b. Suitable means which may include springs thereupon act upon valves *a* and *b* to move the same to operative condition.

In order that there may not be too rapid a movement of the valve piston 14^b which would load the compressor before the prime mover had attained full speed, means are

provided for retarding the downward movement of the piston. Preferred means for this purpose comprise a suitable dash pot device 15 having threaded engagement with a bore 5 in casing 7 communicating with chamber 8 and in line with bore 10^a. This device comprises a cup shaped casing 16 threaded into the aforesaid opening and having its lower open end sealed by a threaded closure member 17 formed with a cylindrical extension 17^a disposed within member 16. A piston 18 has a lapped fit with the interior of cylindrical extension 17^a and a rod 18^a secured thereto extends through a bore in casing 16, 10 through chamber 8, and into the bore of member 11 to engage piston valve 14^b. A coiled spring 19 seated in cylinder 17^a and engaging the piston 18 maintains rod 18^a in yielding engagement with piston valve 14^b. 15 A plug 16^a in the side of casing 16 enables the latter to be partly filled with oil. The oil can pass freely into the lower end of the cylinder 17^a through interconnecting bores 20 and 21, in closure 17, and a passage 22 provided with a check valve 23. Limited reverse flow of the oil from cylinder 17^a to the interior of casing 16 is permitted by a passage 24 controlled by an adjustable plug or needle valve 25. 20 For the sake of clearness the body of oil in dash pot 15 is not shown.

With the compressor at rest the control apparatus is in its normal condition as shown in Fig. 2, the high pressure fluid from the receiver is connected to pipe 9^a through chamber 8, the bore of member 11 and ports 11^a so that the water valve *b* is held closed by pressure fluid and the unloading valves *a* are held open to unload the compressor. On 25 starting the motor rod 14^a carrying piston valve 14^b starts to move down and this movement is resisted by spring 19 of the dash pot and by the oil trapped in the lower end of cylinder 17^a beneath piston 18 so that the latter moves down slowly as the oil is forced out through the restricted passage 24. By 30 the time that piston valve 14^b has passed below and uncovered ports 11^a (Fig. 3) the motor has attained full speed and is able to operate the loaded compressor without 35 stalling or damage, the pressure fluid in pipe 9^a having been vented to atmosphere through ports 11^a, the bore of member 11, and ports 11^b. When the compressor is stopped piston 40 valve 14^b operated by the centrifugal organization X moves upward to again establish communication between valves *a* and *b* and receiver pressure. Rod 18^a of the dash pot maintains contact with the valve piston by 45 reason of spring 19 and the free access of oil to the cylinder 17^a through the check valve 23. Any leakage of pressure fluid along rod 18^a into casing 16 of the dash pot device will not affect operation of the latter 50 since the pressure equalizes on the opposite

ends of the piston 18 due to the free passing of the oil in casing 16 into the lower end of cylinder 17^a past check valve 23.

While but one form of the invention has been herein shown and described it is to be understood that the invention is not restricted to the specific details thereof but covers all changes, modifications and adaptations within the scope of the appended claims.

I claim as my invention:

1. Regulating apparatus for compressors, pumps and the like comprising in combination valves arranged to be rendered inoperative by fluid pressure, a speed responsive device driven by the compressor and having a reciprocating member controlling the admission and exhaust of pressure fluid to and from said valves, a rod maintained in contact with said member, and both fluid means and spring means arranged yieldingly to resist movement of said rod in one direction so as to retard the exhaust of pressure fluid from said valve.

2. In apparatus of the class described, in combination, a casing having chambers connecting with the fluid pressure supply and with the compressor unloading valves respectively, a control member movable automatically in response to the speed of the compressor for connecting said second chamber to said first chamber or to atmosphere, a dash pot device secured to said casing having a member projecting into said chambers and yieldingly engaging said control member for resisting its movement in one direction, and a spring arranged to offer additional resistance to the movement of said control member in said direction.

3. In apparatus of the class described, in combination, a casing having chambers connecting with the fluid pressure supply and with the compressor unloading valves respectively, a control member movable automatically in response to the speed of the compressor for connecting said second chamber to said first chamber or to atmosphere, a dash pot device secured to said casing having a fluid chamber, a cylinder therein, a piston reciprocable in said cylinder, a member projecting from said piston up into the chambers of said casing to engage said control member, and means permitting free flow of fluid into the cylinder beneath said piston but throttling its reverse flow, thereby to delay movement of said control member to compressor loading position.

4. In apparatus of the class described, in combination, a casing having chambers connecting with the fluid pressure supply and with the compressor unloading valves respectively, a control member movable automatically in response to the speed of the compressor for connecting said second chamber to said first chamber or to atmosphere, a dash pot device secured to said casing having a

fluid chamber with an open end, a closure for said open end having an extension within said chamber forming a cylinder, a piston reciprocable in said cylinder and having a stem 5 projecting up into the chambers of said casing to engage said control member, a spring beneath said piston to maintain said stem in contact with said member, and means permitting free flow of fluid into said cylinder 10 beneath said piston and adjustably restricting its reverse flow thereby to delay the loading of the compressor.

5. A dash pot device constructed and arranged to be secured to the automatic control 15 device for valves of a compressor to prevent premature operation of the latter comprising a hollow dash pot casing having an open end, a closure for said open end having a cylindrical extension within said casing, a piston reciprocable within said cylindrical extension and having a stem projecting beyond said casing to engage the control member of said control device, a spring beneath said piston to urge said stem into contact with said member, and means permitting free flow of fluid 20 in said casing beneath said piston and restricting its reverse flow.

6. A dash pot device constructed and arranged to be secured to the automatic control 25 device for the valves of a compressor to prevent premature operation of the latter comprising a hollow dash pot casing having an open end and a perforated projection for at-

tachment to said device, a closure for said open end having a cylindrical extension projecting within said casing and in spaced relation to the walls thereof, a piston reciprocable within said cylindrical extension and forming two chambers within said casing, said piston having a stem extending through 35 said perforated projection of said casing to cooperate with said control device, a spring within said extension yieldingly to maintain said piston remote from said closure, means in said closure member controlling the flow 40 of liquid between said chambers in said casing, said means permitting free flow of liquid into the chamber within said extension but restricting its flow outwardly thereof.

7. Regulating apparatus for compressors, 50 pumps and the like comprising in combination, valves arranged to be rendered inoperative by fluid pressure, a speed responsive device driven by the compressor and having a reciprocating member controlling the admission and exhaust of pressure fluid to and from said valves, a plunger maintained in contact with said member, and both fluid 55 means and spring means arranged yieldingly to resist movement of said plunger in one direction, said spring means being within said fluid means and arranged to assist in the proper functioning of the latter.

Signed by me at Franklin, Penna., this 22d day of July 1925.

LEON F. HOFFMAN.
